UNITED STATES PATENT OFFICE.

CHARLES THEODORE HENNIG, OF LONDON, ENGLAND, ASSIGNOR TO JAMES ROBINSON HATMAKER, OF LONDON, ENGLAND.

CALCINING-FURNACE.

SPECIFICATION forming part of Letters Patent No. 726,915, dated May 5, 1903.

Application filed October 4, 1899. Serial No. 732,471. (No model.)

To all whom it may concern:

Be it known that I, CHARLES THEODORE HENNIG, a citizen of the United States of America, residing in London, England, have 5 invented a certain new and useful Improvement in Calcining-Furnaces, of which the following is a specification.

Owing to the tendency of heated gases to rise and to pass rapidly through a tube of limited length the heat introduced into the rotary furnaces at present used for calcining materials is but poorly utilized, and besides waste of heat considerable power is required to revolve such furnaces.

15 My objects are to effect a higher utilization of the heat employed in calcining and to reduce the expenditure of power in connection with such processes, and to accomplish these ends I construct a furnace consisting of a series of connected and preferably descending elongated chambers, each successive member of which forms an angle with the one preceding it. The course through such a series of chambers being of greater length and being 20 broken or changed in direction the heated gases and the materials passing through it are kept in longer contact than they possibly can be in a single rotary furnace. In cases where the passage of the materials to be treated 25 can be assisted through my series by a screw or other practicable internal means I prefer to make the chambers stationary and more or less flat or low in cross-section, so as to keep the heated gases down near the load 30 to be acted upon; but my invention is not limited in its application to a series of chambers of a particular cross-section nor to stationary chambers, for a series may include 35 rotary, rocking, or other movable chambers. 40 In practice the chambers made be made longer or shorter, the number in a series may be two or more, and their degrees of inclination may vary. I prefer to make the lower or final chamber of my series vertical and stationary, so that the materials treated may fall 45 through it to its point of discharge, the heated gases being introduced into said final chamber near its lower end above its point of discharge and rising upward through it into 50 and through the chamber or chambers above it. The chambers in any given series are

suitably connected to prevent escape of heat and to facilitate the passage of materials. A screw or other suitable conveying means may be employed in stationary chambers to facilitate the passage of materials through them, and baffles may be constructed inside the chambers to deflect or retard the passage of the heat.

55 My invention is illustrated by the constructions shown in the accompanying drawings, in which like parts are designated by like numbers and letters.

Figure I shows a continuous furnace, composed of two descending stationary chambers 60 A and B and a final vertical stationary chamber C. The two upper chambers are made low in cross-section and are fitted with screws 3 3 to assist the passage of materials through them. These screws are supported by hang- 65 ers or supports 6 6 and are connected outside the chambers by a bevel-gear 5 and revolved by power applied at pulley 4. Materials introduced at 1, after passing through the furnace, are discharged at 2. Heated gases from 70 any convenient source, as from the combustion of pulverized coal, are introduced at 7 and, passing upward, carrying the evaporation 75 with them, find an outlet at 8. A door is provided at 9 to admit of access to the chambers, 80 if necessary. A baffle or deflector is shown at 10. Cast-iron or other suitable plates may be inserted along the bottom of the upper chambers to protect the lining from the wear of the screws and of the materials. It will be 85 noticed that no conveying means whatsoever are required in my final vertical chamber, the materials falling through it by gravity. I lay particular stress upon the practical importance and value of this final chamber of 90 my series, for it enables a result to be brought about which is very desirable in the calcination of various materials—namely, a thorough exposure of the materials to be treated to the gases when they are first introduced and at 95 their highest temperature, the gases rising through the falling materials. I prefer to make the walls of this final chamber slightly expanding from top to bottom to prevent contact and adherence of the materials falling 100 through it.

Fig. II shows my furnace composed of a de-

scending stationary chamber A, a descending rotary chamber D, and a final vertical stationary chamber C. This substitution of a rotary chamber in place of the stationary chamber B (shown in Fig. I) is desirable where higher heats are employed, as a rotary chamber is revolved by external application of power, and no internal conveying means which might be unfavorably affected by high temperatures are required. A rocking chamber may be used instead of the rotary chamber without departing from my invention.

Fig. III is a cross-section showing my preferred form of stationary chamber with screw 3 in position and hanger 6 and protecting-plate 11.

It will be understood that the furnace should be built of suitable fire-resisting materials and that the screws or other conveying means within any of the chambers should be made of metals capable of withstanding the effects of the heat employed. For high heats I have found nickel alloys to be the most suitable. The bearings within the chambers should be of graphite or equivalent material.

Although my furnace is especially suited to high temperatures and I have referred to it herein as a "calcining-furnace," it may be used with advantage for roasting or drying at lower temperatures than are ordinarily required for calcining, and I wish it understood that I do not limit its use to what might strictly be called "calcining."

35 What I claim is—

1. A furnace in which materials to be treated are brought into direct contact with heated gases, the said furnace consisting of a final vertical stationary empty chamber in combination with a number of chambers above it, all of the said chambers being connected and

so constructed that each successive chamber in the series forms an angle with the chamber preceding it, the said final chamber being of considerable length and having an opening for the admission of heated gases near its lower end so that the materials falling through it may be thoroughly exposed to the action of the heated gases rising through it and having an opening for the discharge of materials at its lower end below the said admission-opening, the first or uppermost chamber in the series having an opening or openings for the escape of the gases and evaporation and the admission of materials, substantially as described.

2. In a furnace of the class described the combination of one or more interiorly horizontally flattened stationary chambers provided with internal conveying means with a final vertical stationary empty chamber of considerable length and having an opening for the admission of heated gases near its lower end so that the materials falling through it may be thoroughly exposed to the action of the heated gases rising through it and having an opening for the discharge of materials at its lower end below the said admission-opening, the said flattened chamber or chambers being placed above the said final chamber, all of the said chambers being connected and so constructed that each successive chamber in the series forms an angle with the chamber preceding it, the first or uppermost chamber in the series having an opening or openings for the escape of the gases and evaporation and the admission of materials, substantially as described.

CHARLES THEODORE HENNIG.
